United States Patent Office

Des. 227,579
Patented July 3, 1973

227,579

VIDEO TAPE RECORDER OR SIMILAR ARTICLE

Takao Takanashi, Kawasaki, Japan, assignor to
Sony Corporation, Tokyo, Japan

Filed Sept. 2, 1971, Ser. No. 177,540

Term of patent 14 years

Int. Cl. D14—01

U.S. Cl. D26—14 B

FIG. 1

FIG. 3

FIG. 1 is a perspective view of the video tape player or similar article, showing my new design;

FIG. 2 is a rear perspective thereof; and

FIG. 3 is a top plan view thereof.

I claim:

The ornamental design for a video tape recorder or similar article, substantially as shown and described.
